US00D985423S

(12) United States Design Patent (10) Patent No.: US D985,423 S
(45) Date of Patent: * May 9, 2023

(54) FASHION ORNAMENT

(71) Applicant: J. Choo Limited, London (GB)

(72) Inventor: Vanessa Rocha, London (GB)

(73) Assignee: J. Choo Limited, London (GB)

() Term: 15 Years

(21) Appl. No.: 29/765,722

(22) Filed: Jan. 11, 2021

(30) Foreign Application Priority Data

Dec. 29, 2020 (EM) 008373906-0003

(51) LOC (14) Cl. 05-04

(52) U.S. Cl.

USPC D5/63; D2/787; D2/999; D11/184

(58) Field of Classification Search

USPC D2/606, 609, 623, 639, 643, 710, 730,
D2/762, 767, 787, 792, 795, 813, 821,

(57) CLAIM

The ornamental design for a fashion ornament, as shown and described.

DESCRIPTION

The sole FIGURE is a top view of a fashion ornament showing my new design.

Any views of the fashion ornament not shown in the figures (including the front, back, left, right, and bottom views) form no part of the claimed design.

1 Claim, 1 Drawing Sheet
